United States Patent Office

Des. 182,747

Patented May 6, 1958

182,747

COMBINED STORAGE AND DISPLAY CASE

Henry J. Talge, Kansas City, Mo., assignor to John C. Hockery, Kansas City, Mo., trustee for Henry J. Talge and Foster L. Talge

Application February 25, 1957, Serial No. 44,985

Term of patent 14 years

(Cl. D80—9)

Fig. 1 is a top plan view of a combined storage and display case embodying my new design;

Fig. 2 is a side elevational view of same, the opposite side being identical in appearance; and

Fig. 3 is an end elevational view of same, the opposite end being identical in appearance.

I claim:

The ornamental design for a combined storage and display case, as shown and described.
